UNITED STATES PATENT OFFICE.

TIMOTHY ROGERS, OF SPRINGFIELD, OHIO, ASSIGNOR TO THE ROGERS FENCE COMPANY, OF SAME PLACE.

WIRE-FENCE POST.

SPECIFICATION forming part of Letters Patent No. 267,758, dated November 21, 1882.

Application filed July 10, 1882. (No model.)

To all whom it may concern:

Be it known that I, TIMOTHY ROGERS, a citizen of the United States, residing at Springfield, in the county of Clarke and State of Ohio, have invented certain new and useful Improvements in Fence-Posts for Wire Fences; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in posts for wire fences.

My invention relates to a permanent and durable post for wire fences in which the wires are held by clamping the post together.

20 In posts for wire fences as usually constructed the wires are held in hooks, notches, or other like devices attached to or cut in the post. These hooks or tangs are liable to be broken or separated from the post, thus letting 25 the wires upon the ground.

The object of my invention is to have the wire not only protected, but to have the post made in two sections which are easily separated for the purpose of removing the wire in 30 case it may be broken, and to allow a new one to be replaced. These features particularly adapt the post for the use of barbed wire, which cannot be drawn through the holes made for it as wire without the barbs can.

35 Figure 1 is a side elevation of my improved post for wire fences with a cross-section of wires therein. Fig. 2 is a front view of the same.

A is the post, which consists of two sections 40 of channel-rail, forming the upright portion and bifurcating at the ground-line, the ends of the fork being secured to a cast-iron base, b'. Its uprights have a half-round groove, c², on the inside of each section, which, when the 45 two uprights are placed together, form a hole for the wire, as seen in the figures. Generally about three bolts are used to clamp the post together—one at the bottom near the ground-line, one half-way up the post, and one at the 50 top. The latter extends through the ends of a bent cap, c. (Seen in Figs. 1 and 2.) This cap can be made of either wrought or cast

iron. Its object is to protect the wires inside the post from wet, as that part of the wire is most subject to corrosion. Bolt b' at the top 55 is necessarily longer than the bolts b below it. All have threads and nuts to tighten them.

In making use of the post it is set with its base b' across the fence-line, as is customary with this class of posts. The two upper bolts are 60 removed, and the cap c also. The uprights are sprung slightly apart, and the wires a or a' dropped in between the sections until they rest in their respective holes. The post is then closed together and the bolts and cap replaced, 65 as before. Fig. 3 shows the inside of one of the uprights with its half-round grooves in the flanges of the channel-iron.

This post possesses the advantage of lightness, strength, and durability, besides being 70 free from the objections there are to a post of either iron or wood having hooks, tangs, or notches on one side to attach the wire thereto. Bolt b' at the top of the post fills a twofold purpose of connecting the top ends of the two 75 uprights and of fastening the cap c thereon.

The post A being similar in general construction to that shown in an application for a patent for a board fence, I herewith disclaim 80 it in its application for other purposes.

I am aware that parallel uprights each having square slots, which, when the uprights are placed together, form an opening for the rails to pass through are common, and that a cap has been placed upon the top of a divided post 85 to serve as a top connection for the braces, and these I do not claim; but

What I do claim is—

The combination, with a fence-post formed 90 of two parallel wrought-iron sections attached to a base and adapted to be sprung apart at the top, and each having semicircular openings which register with corresponding openings upon its mate, of a cap placed over the top of the sections, and bolts passing through 95 both sections, and the upper one clamping the top of the section and the cap, substantially as described.

In testimony whereof I affix my signature in presence of two witnesses.

TIMOTHY ROGERS.
